MARK A. DEFIBAUGH, OF PEORIA, ILLINOIS, ASSIGNOR TO ALTORFER BROS. COMPANY,
OF PEORIA, ILLINOIS, A CORPORATION OF ILLINOIS

WASHING MACHINE

Application filed February 28, 1927. Serial No. 171,459.

This invention relates to washing machines, and more particularly to the manner of disposing the water-impelling member within the stationary tub thereof.

5 One of the objects of the invention is in the provision of a stationary washing machine tub and a water-agitating or impeller member disposed therein and means for adjusting the vertical position of said impeller within 10 the stationary tub.

Another object is in the provision of a water-impelling member, the same being adapted to be moved in a reciprocatory manner, and manually adjustable mechanism for 15 varying the vertical position of said impeller with respect to a tub member.

Still another object is in the provision of a stationary tub, a water-impelling member 20 adapted for reciprocatory motion therein adjacent the bottom thereof, said tub having a radial depression upon its bottom portion and manually adjustable means for varying the vertical position of said water impeller in such manner that the position of the 25 periphery of the impeller may be adjusted in the radial depression.

A further object lies in the provision of a tub member having a radial depression therein, an impeller capable of reciprocatory 30 movement disposed adjacent the bottom of the tub, said impeller having its periphery fashioned in such manner that it reciprocates within the depression in the bottom of the tub, and mechanism for adjusting the position 35 of the impeller with respect to the radial depression.

Other objects of the invention will appear 40 in the specification, taken in connection with the annexed drawings, in which—

Fig. 1 is a cross-sectional view showing the relationship of the impeller to the washing machine tub; and

Fig. 2 is a cross-sectional view showing in 45 enlarged detail the adjustable mounting for the bladed impeller.

Referring to the drawings, in Fig 1 there is shown a stationary washing machine tub, said tub comprising the vertical side walls 50 10 and the bottom portion 11. The tub has not

been shown in detail, inasmuch as same might be in many shapes or forms.

The bottom 11 of the tub has a radial depression 12 formed therein, as may be clearly seen in Fig. 1 of the drawings. A supporting bracket 13 is either attached to the bottom of the tub at a point therebelow, or may form an integral part of the tub. Screw threaded, as at 14, into an opening in the portion 13, is a supporting column 15. This column is flared, as at 16, at a point adjacent the bottom of the tub, and between the flared portion 16 and the bottom of the tub is ordinarily disposed a gasket 17 providing a water-tight connection about the opening in the bottom of the tub.

55 The supporting column 15 has the internal bearing surfaces 18 and 19, which support a conventional, vertical drive shaft 20. Inasmuch as this type of washing machine is so generally known, the means for reciprocating the vertical drive shaft 20 has not been shown or described, especially in view of the fact that any one of a great number of driving mechanisms might be utilized for the desired 60 reciprocation.

65 A block 21 is fixedly attached to the upwardly projecting end of the drive shaft 20, said block assuming such shape as will obviate the necessity of some connecting means 70 between the later to be described impeller and the block, to provide a driving connection.

A water agitator or impeller is shown generally at 22, said impeller comprising the upwardly projecting stem 23, the bladed water-agitating members 24 and the disk portion 25, the periphery of which is downturned in the manner disclosed at 26, said periphery being adapted to lie partially within the before- 75 mentioned radial depression 12.

80 In the drawings, the stem 23 is a die-cast metal member, while it appears that the disk and bladed members 24 are cast metal. However the particular fashioning of the stem, 85 bladed and disk portions is not material, as far as the present invention is concerned, and might be either cast, die-cast metal or any other material that would be suitable for the purpose. Within the stem 23, and adj- 90 100

cent the upper end thereof, is an inner connecting member 27, which has an opening therein of exactly the same shape as the block 21 and adapted to fit over said block 24 not only to provide a vertically removable connection therewith, but also to provide a satisfactory driving connection.

The impeller is supported at its upper end by the above mentioned driving connection. However, at the lower end, there is found a supporting member 28, screw threaded as at 29 to the lower part of the column 15. A bearing 30 conforming to the shape of the supporting member 28, provides means for centering the impeller at its lower end. Adjustably screw threaded at a point below the supporting member 28 is a lock nut 31.

With respect to the above construction, it might be stated that same generally conforms to a well known type of washing machine, which has a water agitator or impeller member disposed adjacent the bottom of the tub. However, ordinarily, in such construction, the agitator is either raised slightly above the bottom of the tub and reciprocated at this point, or the bottom of the tub is formed in a sort of basin-like manner and the agitator disposed therein. This fashioning of the bottom of the tub in a basin-like manner, with the disposition of the agitator therein, not only necessitates the use of a larger amount of material, but also reduces the efficiency of the agitator, due to the necessity of locating same within said sump-like structure.

Applicant desires that the periphery of the agitator lie as closely to the bottom of the tub as possible in order to prevent the passage of material being washed beneath the agitator, as well as to prevent lodging of extraneous matter beneath the periphery of the disk, which condition has been found, in many instances, to prevent the efficient operation of the machine. Applicant, by a simple arrangement of parts, namely, the stamping of a radial depression in the bottom of the tub and the projection of the periphery of the disk into said depression overcomes any disadvantage that might attend the usual reciprocation of an impeller above the bottom of the tub and at the same time retains the advantages as far as the washing action is concerned.

Applicant also realizing that in mass production of washing machines, no matter how great the attention given to the fashioning of each part, it is impossible for each part of the washing machine, and especially the water-agitating means, to be machined exactly alike, and for this reason he has provided a manually adjustable means for varying the vertical position of the water impeller to take care of any mechanical imperfections that may naturally arise when the machines are produced in large numbers.

With respect to this means for varying

the vertical position of the water agitator, we find that the support 28, which carries the bearing 29, may be raised or lowered by first loosening the lock nut 31. When said support has been moved to the proper position, at which time the periphery 26 of the disk will be disposed partially within the depression 12, the lock nut may be thereafter tightened and the final position of the water impeller determined.

What I claim is:

1. In a device of the class described, a stationary tub, having an opening in the bottom thereof, a vertical drive shaft projecting upwardly through said opening, a supporting column for said drive shaft, a water-impelling member comprising a disk having a plurality of blades thereon, a stem merging with said disk and blades surrounding the column, a driving connection between said stem and the vertical shaft, means for centering the disk adjacent the bottom of the tub, said centering means having a threaded connection with the column and permitting vertical adjustment of the impeller member, and a nut for locking said centering member in fixed position.

2. A device of the class described, comprising a stationary tub, a water impeller therein adapted to lie adjacent the bottom thereof, a driving connection for said water impeller and adjustable mechanism including an adjustable bearing for varying the position of said impeller vertically with relation to the bottom of the tub.

3. A device of the class described comprising a stationary tub having an annular depression therein, a water impeller within said tub comprising a disk, water-agitating means on said disk, the periphery of said disk projecting within the annular depression in the tub, a driving connection for said water impeller, and mechanism for adjusting said water impeller to vary the position of the periphery of the disk with respect to the annular depression.

In testimony whereof I have hereunto affixed my signature.

MARK A. DEFIBAUGH.
